UNITED STATES PATENT OFFICE.

JOSEPH WILLARD GAMBLE, OF PHILADELPHIA, PENNSYLVANIA.

INJECTOR.

SPECIFICATION forming part of Letters Patent No. 602,537, dated April 19, 1898.

Application filed February 11, 1898. Serial No. 669,925. (Model.)

To all whom it may concern:

Be it known that I, JOSEPH WILLARD GAMBLE, a citizen of the United States, residing in the city and county of Philadelphia, State 5 of Pennsylvania, have invented a new and useful Improvement in Injectors, which improvement is fully set forth in the following specification and accompanying drawings.

My invention relates to a valve of special 10 construction adapted to be used in combination with any jet apparatus of the injector type, which is provided substantially with two sets of instrumentalities, one set of tubes being proportioned for lifting the water and 15 delivering it under a moderate pressure to a second set of tubes, where an additional velocity is imparted to the water, enabling it to overcome a comparatively high counter-pressure.

20 In injectors of the usual construction of the double-tube type the pressure at the delivery end of the forcing set of tubes is much greater than the pressure at the delivery end of the suction or supply set of tubes, the 25 ratio of the pressures between the two sets being usually about four and one-half to one; but this ratio may vary considerably, according to the proportions of the tubes, and it is accordingly by taking advantage of this difference in pressure that I am enabled to 30 operate my improved injector without the aid of what is known to those skilled in the art as a "locked overflow mechanism," and I am also further able to produce an injector of 35 compact symmetrical design which will conform to the requirements of modern railroad practice as regards certain external dimensions.

My invention further consists of novel 40 details of construction, all as will be hereinafter fully set forth, and particularly pointed out in the claims.

Figure 1 represents a longitudinal sectional view of an injector embodying my invention. 45 Fig. 2 represents a section on line xx , Fig. 1. Fig. 3 represents a section on line yy , Fig. 1. Fig. 4 represents a section on line zz , Fig. 1. Fig. 5 represents a section on line $x'x'$, Fig. 1. Fig. 6 represents a longitudinal section on line 50 $y'y'$, Fig. 1.

Similar letters of reference indicate corresponding parts in the figures.

Referring first to Fig. 1, A designates the body, B the steam-inlet, C the water-inlet, D the outlet to boiler, and E the overflow, of an 55 injector.

The differential valve to which this invention especially relates is located at the lower portion of Fig. 1 and consists of a cap or plug L, carrying the threaded rings R and R', 60 which are separated by the threaded ribs Q and Q', said plug being adapted to be screwed into the injector-body, as shown in Fig. 1.

The ring R is threaded to receive the valve-seat K, the passage through which latter is 65 adapted to be closed by the check-valve J, by which construction I am enabled to allow the piston M, which is adapted to fit the ring R', to be placed in position, said piston M being secured to the check-valve J by means of the 70 extension J', which is screwed into, pinned, or otherwise secured to a boss on the piston M.

E' designates a chamber in communication with the delivery end of the forcing-nozzle G and leading to the valve J, while S' designates 75 a chamber into which the suction or supply set of tubes delivers the water, said chamber S' communicating with the forcing-nozzle and also by means of the passage G' with the under side of the piston M.

The forcing combining-tube has the rear end thereof threaded at T' and screwed into the adjacent partition in the injector-body, as will be evident from the upper right portion of Fig. 1, while at the forward end of 85 said tube a collar or shoulder T^x is provided, which is adapted to seat on the partition T² of the injector-body, said tube G being provided with vent-holes U' U² for a purpose to be hereinafter described.

90 The operation of the injector is as follows: A movement of the handle S by means of the intermediate mechanism withdraws the spindle W and opens the valve X, attached thereto, which permits steam to enter the chamber L', 95 and thence by the side passages M' (best seen in Fig. 2) to pass into the chamber N'. The steam then blows through the steam suction-nozzle H and suction combining-tube I into the chamber S' and passes through the passage G' under the piston M, lifts the piston and check-valve, and passes through passage H' up under said check-valve, and thence by 100 means of the passage F' out through the over-

flow E. A portion of the steam will pass between the steam-forcing nozzle F and the forcing combining-tube G, and thence through the latter tube into the chamber D' and through the passage E', and while a considerable portion of the steam will escape through the vents or openings U' U² there will be a slight pressure on top of the check-valve J; but the area of the piston M being about two and one-half times the area of the top of said check-valve the piston will open and allow the steam to have a free vent. As soon as the water appears, the spindle W being further withdrawn by an additional movement of the handle S, the plug Z is withdrawn from the opening in the steam-forcing nozzle F, thus admitting steam and driving the water at a high velocity through the tubes and producing a high pressure in the chamber D' and passage E'. Since this pressure is from four to five times as great as that in the chamber S', while the respective areas of the check-valve J and the piston M are in substantially the proportion of one to two and one-half, the greater pressure, though acting on the smaller area, would be sufficient to close said check-valve and hold it to its seat while the injector was in operation.

It will of course be evident that the ratio of the upper or check valve to the lower piston can be varied between considerable limits as may be expedient, and it will further be apparent that the area passing said check-valve and communicating with the passage may be restricted as much as necessary.

By making the vents in the tube G sufficiently large to provide for all the steam that issues from the upper or forcing nozzle the steam might be admitted simultaneously to both steam-nozzles, and the injector would perform its functions of lifting its water-supply and starting to feed automatically.

The openings in the forcing combining-tube are not intended as a vent for the steam from the suction set of tubes, as the suction set of tubes would perform their duty of lifting the water just as well if no openings were provided in the forcing combining-tube; but the object of placing said openings in the forcing combining-tube is as follows: When the water is being driven at a high velocity across these openings, a vacuum is produced, and, such being the case, any slight leakage that may occur around the piston M will be taken up and forced into the boiler, said openings also serving the purpose of providing an overflow momentarily for the forcing combining-tube when the jet is being formed.

The injector may be made to perform its operations of starting automatically as follows: When steam is admitted to both nozzles, the steam from the suction set will pass to the atmosphere, as previously described, while the steam from the upper or forcing set of nozzles which escapes into the chamber S' will take the same course without creating excessive pressure in the said chamber.

It will further be evident that the piston M and check-valve J and their adjuncts may be inserted from the top of the injector and placed much nearer to the steam-inlet, if so desired.

It will be evident that the exit of the steam from the chamber N' is controlled by means of the valve D^X, which is rotatably mounted in the shell or casing C' and actuated by means of the spindle B' and the hand-wheel A'.

It will of course be understood that the present description has been especially confined to the parts which more especially relate to my invention and its specific manner of application, the features of the injector which are old and well known being not specifically referred to.

It will be evident that slight changes may be made by those skilled in the art which will come within the scope of my invention, and I therefore do not desire to be restricted in every instance to the exact construction I have herein shown and described.

Having thus described my invention, what I claim as new, and desire to secure by Letters Patent, is—

1. The combination with an injector of a cap, threaded rings attached thereto, a valve-seat engaging one of said rings, a check-valve movable on said seat, a piston movable in the other of said rings and connections common to said piston and valve.

2. In an injector, a casing, a lifting set and a forcing set of tubes, a device adapted to be inserted in said casing and consisting of a plug, threaded rings attached thereto, and adapted to engage suitable portion of said casing, a valve-seat adapted to engage one of said rings, a check-valve movable on said valve-seat, a piston closing the opening through one of said rings and connections common to said valve and piston.

3. In an injector provided with a lifting set and a forcing set of tubes, the combination of a differential check-valve and piston adapted to receive the pressure from the primary set of tubes on the under side of the piston and the pressure from the secondary set of tubes on the valve side of said differential valve and piston.

4. In an injector provided with a lifting set and a forcing set of tubes, the combination of a device consisting of a check-valve having a piston connected thereto, a communication on the valve side of said device with the delivery end of said forcing set and on the piston side of said device, with said lifting set and a communication provided, when said valve is raised, with a chamber closed by a check-valve which in turn communicates with the atmosphere.

5. In an injector provided with a lifting set and a forcing set of tubes, the combination of a differential valve and its adjuncts constructed substantially as described and a forcing combining-tube, the latter being provided with sufficient vents to enable the steam from

the forcing steam-nozzle to pass away, thereby dispensing with all operating mechanism and rendering the injector automatic in its action.

5 6. In an injector provided with a lifting set and a forcing set of tubes, the combination of a differential valve for the purposes described and means whereby the leakage through the piston of said valve may be taken up by the 10 suction produced by the forcing combining-tubes.

7. In an injector, a lifting set and a forcing set of tubes, a check-valve and a piston connected to said valve, said piston and valve 15 being of different areas, and means for enabling the leakage through the said piston to

be taken up by the suction created by the forcing combining-tubes.

8. In an injector, a casing, a lifting set and a forcing set of tubes, threaded rings engaging the interior of said injector, a check-valve and piston of different areas connected together and movable in said rings, means for conducting pressure from the primary set of tubes to the under side of said piston, and 20 means for conducting pressure from the secondary set of tubes to the top of said valve. 25

JOSEPH WILLARD GAMBLE.
